(No Model.)

A. A. SMITH.
BOB SLED.

No. 549,402.

Patented Nov. 5, 1895.

UNITED STATES PATENT OFFICE.

ANDREW A. SMITH, OF HOTCHKISS, ASSIGNOR OF ONE-HALF TO WILLIAM R. GALE, OF DELTA, COLORADO.

BOB-SLED.

SPECIFICATION forming part of Letters Patent No. 549,402, dated November 5, 1895.

Application filed June 8, 1895. Serial No. 552,072. (No model.)

To all whom it may concern:

Be it known that I, ANDREW A. SMITH, a citizen of the United States, residing at Hotchkiss, Delta county, Colorado, have invented 5 certain new and useful Improvements in Bob-Sleds, of which the following is a full, clear, and exact specification, reference being had to the accompanying drawings, in which—

Figure 1 is a perspective of the bob-sled. 10 Fig. 2 is a side elevation of the front sled. Figs. 3 and 4 are details.

The invention relates to that class of sleds or sleighs known as "bob-sleds."

The object of the invention is to provide a 15 sled of this description which shall be simple, strong, and durable.

The invention will first be described, and then specifically pointed out in the claims.

A is the front sled, B the rear sled, and 20 C is the reach, which connects them adjustably. The front and rear sleds are constructed alike and each consists in the transverse beam D, provided at its ends with depending knees D', formed with a horizontal top cross-piece d, bolted to the under side of beam D, from the 25 ends of which depend the side bars d' d', which converge toward their lower apertured ends, while from the front and rear edges of this cross-bar d extend the curved guides or guards 30 d², having a pair of side flanges or ears d³ at both ends.

E are the runners, formed of the flat steel shoes E', curved upwardly at their forward ends and having wooden braces E² on their 35 upper sides. Each runner E is provided with a curved or segmental standard F, bolted at its ends thereto and having a perpendicular middle portion or brace F', formed at its lower end with a foot F², bolted to the runner in a 40 cut-away portion e² of the brace E². The upper side of the brace E² is rounding, and the ends of the standards F are provided with concave feet f, which rest upon the curved faces of the braces E² and are bolted to the 45 runners. The knees D' straddle the curved standards F and are pivoted at their lower rounded ends by pivots f' to the lower end of the braces F', said lower rounded ends resting on the upper sides of the feet F², so 50 that the whole weight of the load will be car-

ried by the knees and not strain the pivots f'. These pivots f' form the axes of the runners, and the curved standards and guards or guides d² are concentric therewith.

G are braces bolted to the beams D and to 55 the forward ends of the guards d² to hold them rigidly in position, and thereby stay the standards F and the runners against all lateral or twisting movement.

The middle portions or braces F' of the 60 curved standards F are each formed of parallel plates bolted at their upper ends to the sides of the standards and bent outward at their lower ends to form the foot F²; but said middle portion or brace F' may, if desired, 65 be integral with the standard F.

The knees D' are each provided with a pair of ears d⁴ on their forward edges, and to the inner ears d⁴ of the rear knees are pivoted the rear ends of a pair of braces H H, the 70 forward ends of which are pivoted to the ends of a tubular slide I, which slides freely on the reach C, the reach being provided with a longitudinal series of apertures c, through which aperture in the top and bottom of the slide a pin i may be passed. The beam D of the rear sled carries a double 75 N-shape clip J, which straddles it and extends below it a sufficient distance to permit the reach to pass through it and rest on its lower 80 front and rear cross-bars j j. A pin K passes through an aperture in the middle of said rear beam and through any one of the apertures c. Thus by removing pins i K the rear sled may be adjusted longitudinally 85 along the reach to bring it into proper relation to the front sled. All mortising of the rear beam D is thus obviated by the use of the clip J.

The front end of the reach C extends under 90 the beam D of the front sled and is there provided with a draft-clevis L, which is formed of a plate bent upon itself and embracing the upper and lower sides of the said front end of the reach with its apertured rear ends. 95 The upper side of the said front beam D is provided with an apertured wear-plate d⁶, over which extends the front apertured end of the brace C', which is bolted at its rear end to the upper side of the reach C. A 100

king-bolt L' passes down through the front bolster M, the brace C', plate d⁶, clip L, and reach C and forms the axis on which the front sled turns horizontally. No rear bolster is necessary with my improved bob-sled. The bolster M and the rear beam D are provided with any form of standards m for holding the load in place.

N is a curved brace pivoted or bolted at its middle between the two sides of the clevis L and at its ends pivoted or bolted to the inner ears d⁴ of the front bolsters D'.

O is the tongue, pivoted at its rear end to the front end of the clevis L and provided with the usual draft attachments.

O' are two braces, secured at their forward ends to the tongue and at their rear ends pivotally connected to the ears n on the brace N between its middle and ends.

20 The operation and uses will be readily understood from the foregoing description.

It will be seen that as the knees D' are each provided with two ears d⁴ any knee will answer for either end of the beams D; 25 also, that the upper sides of the beams D are wholly free from any projecting portions of the runner mechanism, as every part thereof is beneath the beams.

Having thus described the invention, what 30 is claimed is—

1. The combination with the front and rear sleds, having cross-bars provided with depending knees to which the runners are pivoted, of a reach extending under both beams 35 and pivoted by a king bolt to the front beam, a double clip embracing the rear beam and extending down below its under side and embracing the reach with its sides or ends and lower cross-bars, and a pin passed through 40 the rear beam and any one of a series of apertures in the reach and between the front and rear cross bars of the clip and braces extending forwardly from the rear knees to a slide mounted adjustably on the reach, substantially as set forth.

2. In a bob-sled, the knee comprising a top cross bar adapted to be bolted to the under side of the beam, side arms depending therefrom and converging toward their lower 50 transversely apertured ends and the integral guards or guides d² d³ projecting from the front and rear of the upper end of the knee and forming slideways for a curved runner standard, substantially as set forth.

55 3. In a bob-sled, the knee comprising a top cross bar adapted to be bolted to the under side of the beam, side arms depending therefrom, and converging toward their lower apertured rounded ends, the front and rear 60 guards or guides integral with the upper end of knee and the apertured ears on forward edges of the side arms, substantially as set forth.

4. The combination with the beam-knee 65 having depending side arms converging at their lower apertured ends, and the integral

oppositely projecting guards or guides at the upper end, of the segmental runner-standards working between said side-arms and guided in said guards or guides; the said 70 standards being provided with a middle portion to which the lower ends of the said knee-arms are pivoted, substantially as set forth.

5. The combination with the beam-knee having depending side arms converging at 75 their lower rounded apertured ends and the integral oppositely projecting guards or guides at the upper end of the knee, of the segmental runner-standard having a middle portion or brace provided with a foot at its 80 lower end on which the lower rounded ends of the knee-arms rock; said lower ends embracing and pivoted to the lower end of the said standard brace or middle portion, substantially as set forth.

6. The combination with the runner having a segmental or curved standard of the beam-knee having side arms and integral oppositely projecting guards straddling the said standard and pivotally connected at the lower 90 ends of the side arms with the runner between the ends of the standard; the lower rounding ends of said side arms resting upon the upper side of the runner or an attachment thereof to take the strain off of the pivot, 95 substantially as set forth.

7. The combination with the beam and the depending knees secured at their upper ends to the lower side of its ends; said knees each comprising depending side arms having apertured rounded lower ends and the integral 100 oppositely projecting guards or guides at the upper end of the knees, of the runners, each having a segmental standard working between the knee arms beneath the beam and provided with a middle portion or brace having a foot at its lower end secured to the runner; the lower rounded ends of the knee being pivoted to the lower end of said middle portion or brace and rocking on said foot, 105 substantially as set forth.

8. The combination with the beam and the runners having segmental standards, of the knees depending from the lower sides of the beam ends and pivotally connected at their 115 lower ends with the runners intermediate of the ends of said segmental standards, the integral guards or guides extending front and rear from the upper ends of the knees and braces extending from the forward guides or 120 guards to the beam, substantially as set forth.

9. The rear sled comprising the beam having a depending middle clip and pin for the reach and depending knees at its ends each having integral front and rear guards or 125 guides and integral depending side arms, the reach-slide having an adjusting pin and connected to said knees by braces, and the runners, each having an arched or segmental standard or brace working between the knee 130 arms and guards or guides, and a perpendicular middle portion or brace secured to

the runner, and to the lower end of which the lower ends of the knee arms are pivoted, substantially as set forth.

10. The combination with the front and rear sleds and a reach extending from the rear sled and pivoted to the cross bar of the front sled and there provided with a clip, of the rigid brace connected at its middle to the said clip and at its ends to the knees of the front sled, and the tongue pivoted at its rear end to the front end of the clip, substantially as set forth.

11. The combination with the front sled having the knees and segmental standards connecting its beam and runners, of the clevis or clip for connecting the tongue and front end of the reach, the rigid curved brace se-

cured at its middle to the said clevis or clip and at its rear ends to the said knees, substantially as set forth.

12. The combination with the front sled, and the rigid curved brace connected at its rear ends to the knees, the clevis or clip to embrace the front end of the reach and to which the said curved brace is secured at its middle, the tongue connected to the front end of clip or clevis and braces extending rearwardly from the tongue to said curved brace, substantially as set forth.
